UNITED STATES PATENT OFFICE

2,477,191

TOBACCO CURING BURNER

Rustic A. Maultsby, Bolivia, N. C.

Application February 25, 1947, Serial No. 730,709

2 Claims. (Cl. 158—80)

1

The present invention relates to improvements in burners and more particularly to burners of the type especially adapted for use in tobacco curing barns.

An important object of the invention is to provide a burner adaptable for use with high grade or low grade fuel oil, in which an even and thorough combustion takes place, with the resultant even distribution of heat for effectively curing tobacco suspended throughout the entire area of the barn.

Another object of the invention resides in the provision of a burner embodying means for directing the fuel from the centralmost portion of the burner through spaced vertical channels to a point on the outside thereof, whereby to assure an even and thorough combustion of the fuel.

A further object of the invention resides in the provision of tapered fin-like members on the outside of the burner for spreading the fuel and resultant flame, said tapered fin-like members terminating in a flanged receptacle which forms the base of the burner.

The above and other objects of the invention will in part be obvious and will in part be hereinafter more fully pointed out.

Figure 1 is an elevational view of the new and improved burner;

Figure 2 is a vertical sectional view thereof;

Figure 3 is a longitudinal sectional view taken substantially on line 3—3 of Figure 2;

Figure 4 is an enlarged vertical sectional view similar to Figure 2 with parts removed; and

Figure 5 is a longitudinal sectional view taken substantially on line 5—5 of Figure 4.

Referring to the drawing for a more detailed description thereof, the new and improved burner construction which is generally designated by the reference numeral 8 includes a dome-shaped housing 9 within which is supported the burner, generally designated by the reference numeral 10.

The housing 9 is formed with an annular flange 11 which is secured by means of bolts or the like 12 to a base member 13. This base member forms the supporting means for the burner 10, as more clearly shown in Figure 2, said burner being supported on legs 14 which are welded or otherwise suitably attached to the base 13. Formed integrally with and extending downwardly from the top wall of the housing 9, there is a hollow tubular-shaped member 15 which terminates substantially midway of said housing. This member 15 is open to the atmosphere for

supplying air to the burner 10. A pair of tapered outlets 16 extend diametrically of the housing 9, and attached thereto are the flues 17 which are directed throughout the area of the tobacco curing barn, and through which the heated gases from the burner are expelled. The manner in which the flues 17 are attached to and associated with the barn form no part of the present invention.

As before indicated, the burner 10 is carried by and rests upon the base 13 and, as shown in Figure 2 of the drawing, is positioned so that the upper end thereof extends within the open end of the tubular member 15, whereby air from the outside of the housing 9 can be admitted to the burner. The burner 10 includes a disk-shaped receptacle 18 having upwardly and outwardly extending walls 19. Cast integrally with and extending upwardly from the bottom wall of the receptacle 18, there is a tubular member 20, which member is open at its upper end. Fuel oil of the low grade or high grade type is fed to the burner from a source, not shown, through the pipe 21. A second pipe 22 is connected by means of an elbow 23 to the pipe 21, this second pipe passing upwardly through the base 13 and the receptacle 18. The upper end of the pipe 22 is, of course, open so that the fuel oil will travel upwardly therethrough to be directed downwardly along the outside of said pipe.

For directing the fuel oil downwardly on the outside of the pipe, there is provided a member 24. This member 24 is also tubular in shape, and has a top wall 25 which rests upon projections 26 formed integrally with the upper end of the pipe 22. Similar projections 27 are formed on the outer periphery of the pipe 22 near the bottom end of the member 24, and by reason of the projections 26 and 27, said member 24 is held in spaced relation on the pipe 22. It will also be noted that the member 24 is equally spaced from the walls of the tubular member 20. Thus the fuel oil entering the pipe 22 will be deflected against the top wall 25 and then be caused to be directed downwardly along the outside of the pipe 22, and thence upwardly through the space 28 between the members 20 and 24.

The upper end of the tubular member 20 supports a deflecting plate 29, said deflecting plate being carried on pins 30 which project vertically from said member 20. The deflecting plate 29 functions to deflect the fuel and flame downwardly along the outside of the tubular member 20.

3

The tubular member 20 has formed integrally therewith a series of fin-like members 31. These fin-like members are arranged in spaced relation on the member 20 and taper from the upper end thereof downwardly into engagement with the outwardly extending wall 19 of the receptacle 18. Thus the fuel and flame will be directed from the deflecting plate 19 downwardly along the tapered fin-like members 31, causing further and more complete combustion of the fuel prior to its entrance into the receptacle 18. The products of combustion from the burner pass upwardly and outwardly through the flues 17.

From the above description when taken in connection with the accompanying drawing, it is believed that the operation and advantages of the new and improved burner are readily apparent. When initially starting the burner, the fuel oil is turned on and fed to the receptacle 18 by passing through the pipe 22, downwardly between the pipe and the member 24, upwardly through the space 28, and then downwardly along the tapered fin 31. Air for supporting combustion is admitted through the hollow tubular shaped member 15. Upon the application of a flame to the receptacle 18, the fuel oil will immediately become ignited with the flames thereof, thus completely enveloping the fin-like members 31 and thereby assuring an even and thorough combustion of all of the fuel being fed thereto. This even and thorough combustion of the fuel develops an even temperature of heat which will be directed throughout the barn by means of the flue 17. This even temperature of heat assures a thoroughly efficient curing of the tobacco suspended in the barn.

It will be further seen that the hollow tubular-shaped member 15 creates a down draft on the burner 19 which will force the flame down and between the fin-like members 31. These fin-like members heat the burner so that all of the fuel will become vaporized, thereby maintaining the burner clean and free from carbon.

The deflecting member 29 can be adjusted and is preferably designed for minute adjustment in order for the burner to have a proper draft and therefore be free from smothering. The fin-like members 31 function to transfer the heat from

within the burner to thereby obtain the greatest heating ability for thorough vaporization of the fuel.

It is obvious that many changes may be made in the details of construction without departing from the spirit of the invention as set forth in the appended claims.

I claim:

1. An oil burner comprising a burner member having a chamber at its base, a pipe for feeding fuel centrally of the chamber, a hood-like covering carried by and spaced from the upper end of said pipe for directing fuel downwardly on the outside thereof, a tubular member extending upwardly from said chamber and surrounding said hood, and tapering fin-like members extending from the upper end of said tubular member downwardly into said chamber.

2. An oil burner comprising a burner member having a chamber at its base, a pipe for feeding fuel centrally of the chamber, an inverted tubular-shaped member carried by and spaced from the upper end of said fuel pipe for directing fuel downwardly on the outside thereof, a tubular member integral with and extending upwardly from said chamber, deflecting means carried on the upper end of said tubular member, and tapering fin-like members extending from the upper end of said tubular member downwardly into said chamber.
